UNITED STATES PATENT OFFICE.

JOHN MAGEE, OF DETROIT, MICHIGAN, ASSIGNOR TO DIAMOND POWER SPECIALTY COMPANY, OF DETROIT, MICHIGAN, A CORPORATION OF MICHIGAN.

WATER-TUBE BLOWER.

1,060,923.

Specification of Letters Patent.

Patented May 6, 1913.

Application filed May 16, 1912. Serial No. 897,762.

To all whom it may concern:

Be it known that I, JOHN MAGEE, a subject of the King of England, residing at Detroit, in the county of Wayne and State 5 of Michigan, have invented new and useful Improvements in Water-Tube Blowers, of which the following is a specification.

This invention relates to the class of blowers or cleaners employed for removing soot 10 from water-tube boilers, and comprising one or more jet pipes or tubes arranged in the combustion chamber between or adjacent to the boiler tubes to be cleaned. Heretofore such blowers have been permanently 15 placed in the combustion chamber, unprotected from the heat, but this is objectionable because the blowers are burned out in a comparatively short time and require frequent renewal. To overcome this objection, the blowers or blower-tubes have been 20 removably arranged in the combustion chamber, so that they could be withdrawn therefrom when not in use. This construction is comparatively expensive and less 25 convenient in use than a blower permanently installed in the combustion chamber.

One of the objects of my invention is the provision of a blower of this type which may be permanently installed in the combustion chamber and which is at the same 30 time provided with cooling means to protect it from the destructive action of the heat and lengthen its life.

A further object is to provide a blower 35 which will reach practically all the boiler tubes and thoroughly clean them.

In the accompanying drawings consisting of 3 sheets: Figure 1 is a fragmentary transverse section of a boiler of the Babcock and Wilcox type equipped with a transversely disposed blower embodying the invention. Fig. 2 is a longitudinal section, on an enlarged scale, of the front or outer portion of 40 said blower. Fig. 3 is a similar section of the rear or inner portion thereof. Fig. 3^a is a similar section of an intermediate portion 45 thereof. Figs. 4, 5, 6 and 6^a are transverse sections on the correspondingly-numbered lines in Fig. 2. Fig. 7 is a fragmentary longitudinal section of a Babcock and Wilcox boiler equipped with a longitudinally-disposed blower containing the invention. Fig. 8 is a longitudinal section, on an enlarged scale, of the outer portion of said 50

blower. Fig. 9 is a similar section of its inner portion. Fig. 10 is a vertical section of a vertical-tube boiler equipped with the improved blower.

Similar characters of reference indicate corresponding parts throughout the several views.

Referring to Figs. 1-6, 1 indicates the walls of the boiler setting and 2 the water tubes communicating at their ends with the customary headers 3 and 4.

The blower comprises a shell or casing 5 arranged on the outer side of the boiler setting and a jet or blower-tube 6 connected with said shell and extending through an opening in the adjacent wall of the setting 10 into the combustion chamber, said tube being disposed transversely between or among adjacent rows of water tubes, as shown in Fig. 1, and having nozzles or jet-openings 7 arranged to direct blasts of steam among 15 or between the tubes. The shell is provided with internal transverse partitions 8 and 9, between which is formed a steam inlet chamber 10 with which is connected a steam supply pipe 11 controlled by a valve 12. The 20 blower tube 6 is arranged axially in the shell 5 and closely fitted in openings in the partitions 8 and 9, the portion of said tube between the partitions being provided with 25 one or more steam inlet openings 13 communicating with said chamber, while the outer end of said tube is closed by a head or plug 14 bearing against the outer side of the partition 9 and preferably rotatable in the shell 5. The blower tube is secured to this plug 30 by any suitable means, so as to turn therewith and the plug is in turn rotated by a rotary disk 15 connected therewith by longitudinal pins 16 preferably secured to the disk and entering sockets in said plug. This 35 disk has a stem 17 extending through a stuffing box 18 at the outer end of the shell and is provided at its projecting end with a hand wheel 19, or other suitable means, for turning it. The disk 15 is held in place in 40 the shell by the outer cap 20 of the shell, as shown in Fig. 2. A drip pipe 21 having a hand valve 22 is connected with the lower side of the steam inlet chamber 10 for carrying off the water of condensation.

Surrounding the blower tube 6 is a tube, hood or jacket 23 which protects the same from the heat of the combustion chamber

and also forms a part of the cooling means hereinafter described. This jacket is provided with openings into or through which the jet nozzles or nipples 7 extend. It is 5 undesirable to subject these jet-nozzles to the strain of transmitting the turning movement of the blower-tube to the jacket, and separate means of any suitable construction are therefore preferably employed for this 10 purpose. The preferred devices illustrated in the drawings consist of radial clamping screws 23^a arranged in threaded openings of the jacket and bearing against the outer side of the blower-tube, as shown in Figs. 2 15 and 6^a, thus relieving the jet nozzles from such turning strains. A single row of such screws located near the blower-inlet is shown in the drawings, but one or more additional rows may obviously be employed at other 20 points, if desired. The jacket 23 is suitably supported in the wall of the boiler setting opposite that near which the shell 5 is arranged and its inner end is preferably serrated, as shown at 24, to form a drill by 25 which the jacket, on being rotated by the hand wheel 19, bores its own supporting socket or groove in the adjacent wall 1. The jacket extends into the inner end of the shell 5 through a stuffing box 25 and is 30 sufficiently larger in diameter than the blower tube 6 to leave an intervening annular passage 26 for a suitable cooling agent, preferably a liquid such as water. This passage communicates at its outer end with 35 a water outlet chamber 27 formed in the shell on the inner side of the partition 8 and having a discharge pipe 28 leading to the drip pipe 21.

Arranged concentrically within the blower 40 tube 6 and separated therefrom by an intervening steam space or passage is a direct pipe or conduit 30 for the water or other cooling agent. This pipe extends through the plug 14 and communicates with a water 45 inlet chamber 31 formed in the shell between said plug and the disk 15. Leading to said chamber is a valved supply pipe 32. In the preferred construction shown in the 50 drawings, the direct water pipe 30 is removably screwed into the plug 14 and clamped therein by a nut 33. The inner end of the blower tube 6 is closed by a plug 34 through which the water pipe 30 passes, and said water pipe is closed at its inner end by 55 a plug 35 preferably formed integral with a larger plug or partition 36 which is arranged in the jacket 23 near its serrated end. The water pipe is removably supported in the plugs 14 and 34 and upon the plug 35. 60 This construction permits the ready removal of the water pipe for cleaning it, after removing the cap 20 and disk 15. Between the plugs 34 and 36 the direct water pipe or passage 30 is provided with a number 65 of openings 37 through which the water es-

capes into the jacket 23 and thence through the return passage 26 into the water discharge chamber 27.

There is a difference in expansion between the blower-tube 6 and the jacket 23, and in order to minimize the resulting strain upon the jet-nozzles 7, the blower tube is preferably provided with one or more suitable expansion joints, particularly in comparatively long blowers. Ordinarily one such joint located about six feet from the first 70 nozzle nearest the blower-inlet is sufficient. In the preferred construction shown in Fig. 3^a of the drawings, the expansion joint consists of a tight slip joint 6^a formed by making the blower tube in sections which are 80 telescoped.

It will be understood from the foregoing that upon opening the valve 12, steam is admitted to the inlet chamber 10 of the shell whence it passes through the openings 13 into and through the blower tube and thence issues through the several jet nozzles 7 against and among the water tubes of the boiler. These nozzles are preferably arranged at suitable intervals on one side of the blower tube, to concentrate the steam jets upon the boiler-tubes, and by rotating the blower-tube, as before described, all portions of the boiler tubes are subjected to the 90 action of the blower and thoroughly cleaned. A single blower is shown in the drawings, but in practice two or more may be installed at proper elevations or intervals to reach and thoroughly clean all of the boiler-tubes. 100

While the blower is not in use, water or other cooling agent is caused to circulate around the blower or blower-tube 6 by opening the valves of the water supply pipe 32 and the discharge pipe 28. The water entering the inlet chamber 31 passes through the direct pipe or passage 30, and the openings 37 into the surrounding jacket 23, whence it returns through the passage 26 into the outlet chamber 27 from which it 110 is discharged through the pipe 28 into the drip pipe 21.

By maintaining a circulation of water or other suitable cooling agent through or around the blower tube, or both, as shown 115 in the drawings, the same is no more liable to burn out than the water tubes of the boiler which have a similar circulation, thus materially prolonging its life. This cooling provision makes it practicable to permanently install the blower in the combustion chamber among the boiler tubes, rendering the blower more convenient in use by avoiding the necessity of withdrawing it from the combustion chamber and also materially 120 reducing the cost of manufacturing and installing the blower. At the same time the apparatus in no way interferes with the draft.

The water supply pipe 32 and the water 130

discharge pipe 28 of the blower preferably have no connection with the water space of the boiler, but are wholly independent thereof. This arrangement effectually avoids 5 clogging of the water passages of the blower by the precipitation of the lime or other sediment in the water, which would be liable to occur if hot water from the boiler were supplied to the water jacket of the blower.

10 It will be noted that in the blower just described the steam and the cooling agent are both supplied to the blower and discharged therefrom at the same side of the boiler. Such a return type of blower is designed more particularly for use in connection with boilers arranged side by side in a battery or batteries, where the shell 5 and pipe connections can be installed only at the outer or accessible wall of the boiler setting.

15 In cases where it is practicable or preferable to provide the blower with supply connections for the steam and the cooling agent at one end and with discharge connections at the opposite end, a blower of the modified construction shown in Figs. 7, 8 and 9 may be employed. In Fig. 7 such a blower is shown as applied to a Babcock & Wilcox boiler, the blower being arranged 20 lengthwise of the boiler and replacing one of the tubes. In practice, one or more blowers are thus disposed at suitable points to reach and clean all of the tubes; for example, the two tubes marked 2^a in Fig. 1, may be replaced by such longitudinal blowers. Referring to this modification of the invention, the central water inlet pipe 30 of the first described construction is omitted and the jacket or protecting tube 38 of the 25 blower-tube 39 extends through suitable stuffing boxes or fittings in the headers 3 and 4, and its upper end passes through a stuffing box 40 into an inlet chamber 41 for the water or other cooling agent formed in the adjacent portion of the shell 42, said chamber having a supply connection 43. As in the first-described construction, the blower tube 39 is arranged concentrically within the jacket 38 and separated therefrom by a water passage 44 extending throughout its 30 length. This passage communicates at its rear end with a suitable connection 45 applied to the rear end of the jacket and leading to the discharge pipe 46. The blower tube and jacket are connected by the jet nozzles 47 and screws 23^a, as in the construction first described. Likewise the outer end of the blower pipe is arranged in the steam inlet chamber 48 of the shell 42 and communicates therewith by openings 49. 50 indicates the inlet connection of said steam chamber. At its outer end the blower-tube is closed by a plug or head 51 having a circular flange 52 rotatably seated between an 35 internal shoulder 53 of the shell and a nut

54. Connected with the outer end of this head is the stem or spindle 55 of the hand wheel 56 by which the blower is turned. The stem 55 is preferably disposed horizontally and inasmuch as the blower tube follows the inclination of the boiler tubes, it is necessary to provide a universal joint 57 of any suitable construction between the stem and said head.

70 As shown in Fig. 9, the rear end of the blower tube is closed by a plug 58.

In the use of this blower which may be termed the "direct" type, the steam entering through the inlet connection 50 passes through the openings 49 into the blower tube 39 and escapes through the jet nozzles 47, cleaning the boiler tubes. The water or other cooling agent admitted through the inlet connection 43 enters the chamber 41 and passes through the space or passage 38 between the blower tube 39 and the jacket 38 into the discharge pipe 46, thus cooling the blower-tube throughout its length.

75 My improved cooled blower, both in its direct and return forms, is also applicable to various other kinds of boilers. For example, in Fig. 10, is shown a water tube boiler of the vertical type equipped in the upper portion of its combustion chamber with a direct blower 59, similar to that shown in Figs. 7-9, and in its lower portion with a return blower 60, similar to that shown in Figs. 1-6. In this case, both blowers extend transversely of the combustion chamber and among the boiler tubes.

80 Other changes or modifications may obviously be made within the scope of the appended claims, and I do not therefore wish to be limited to the particular constructions herein shown and described.

85 I claim as my invention:

1. In a boiler, the combination with the combustion chamber and the boiler-tubes, of a soot-blower arranged in said chamber adjacent to the boiler-tubes to remove the soot therefrom, and means for supplying a cooling liquid to the blower.

90 2. In a boiler, the combination with the combustion chamber and the boiler-tubes, of a soot-blower arranged in said chamber adjacent to the boiler-tubes to remove the soot therefrom, a jacket inclosing the blower, and means for supplying a cooling agent to said jacket.

95 3. The combination with the boiler setting, the combustion chamber and the boiler-tubes, of a soot-blower comprising a blower-tube permanently arranged in the combustion chamber adjacent to the boiler-tubes to remove the soot therefrom, a cooling-conduit adjacent to said blower-tube, and a connection arranged on the outer side of the boiler-setting for supplying a cooling agent to said cooling conduit.

100 4. The combination with the boiler set-

130

ting, the combustion chamber and the boiler-tubes, of a soot blower comprising a casing arranged on the outer side of the setting and having separate inlet chambers for steam and a cooling agent, a blower tube permanently arranged in the combustion chamber adjacent to the boiler-tubes to remove the soot therefrom, said blower-tube being connected with said steam inlet chamber, and a cooling conduit associated with said blower-tube and connected with said cooling-agent chamber.

5. In a boiler, the combination with the combustion chamber and the boiler-tubes, of a soot-blower arranged in said chamber adjacent to the boiler-tubes to remove the soot therefrom, and cooling means associated with said blower and independent of and disconnected from the water space of the 20 boiler.

6. In a boiler, the combination with the combustion chamber and the boiler tubes, of a soot-blower arranged in said chamber adjacent to the boiler tubes to remove the soot 25 therefrom, a jacket inclosing the blower, and means for supplying a cooling agent to said jacket disconnected from the water-space of the boiler.

7. A soot-blower comprising a casing having separate inlets for steam and a cooling agent, a blower-tube connected with said steam inlet, and a cooling-conduit adjacent to the blower-tube and connected with said cooling-agent inlet.

35 8. A soot-blower comprising a casing having separate inlets for steam and a cooling agent, a blower-tube connected with said steam inlet, and a cooling jacket surrounding the blower tube and connected with said 40 cooling-agent inlet.

9. A soot-blower comprising a blower-tube, a protecting jacket surrounding said tube and provided at its inner end with boring means adapted to penetrate the boiler 45 setting, and means for rotating said jacket.

10. A blower comprising a casing having a steam inlet chamber, a blower-tube communicating with said chamber, a protecting jacket surrounding the blower tube and provided at its inner end with boring means adapted to penetrate the boiler-setting, and means for rotating said jacket.

11. A blower comprising a casing having a steam inlet chamber, a blowertube communicating with said chamber and rotatable in said casing, means for rotating the blower tube, a protecting jacket surrounding the blower tube and provided at its inner end with boring serrations, and means connecting the jacket with the blower-tube to compel it to turn therewith.

60 12. A soot-blower, comprising a casing having a steam inlet and an inlet and an outlet for a cooling agent, a blower-tube com-

municating with said steam inlet, and direct 65 and return conduits for the cooling agent arranged adjacent to the blower tube and respectively connected with said second-named inlet and said outlet.

13. A soot-blower, comprising a casing 70 having a steam inlet and an inlet and an outlet for a cooling agent, a blower-tube communicating with said steam inlet, a direct conduit for the cooling agent arranged within the blower-tube and communicating with 75 said second-named inlet, and a return conduit for the cooling agent surrounding the blower-tube and communicating with said outlet.

14. A soot-blower comprising a casing 80 having a steam inlet chamber, an inlet chamber for a cooling agent and an outlet for said agent, a blower tube extending into said casing and communicating with said steam inlet chamber, a pipe arranged within the 85 blower tube and communicating at its receiving end with said inlet chamber for the cooling agent, and a cooling jacket surrounding said blower-tube and communicating at one end with the delivery end of said pipe 90 and at its opposite end with said outlet.

15. A soot-blower comprising a casing having a steam inlet chamber, an inlet chamber for a cooling agent and an outlet for said agent, a blower-tube extending into 95 said casing, communicating with said steam inlet chamber and closed at its opposite end, a pipe arranged within the blower-tube and communicating at its receiving end with said second-named inlet chamber, the opposite end of the pipe extending through the closed end of the blower-tube and having a discharge opening in its projecting portion, and a cooling jacket surrounding said 100 blower-tube and closed at its inner end, said inner portion of the jacket communicating with the projecting portion of said pipe and the opposite end of the jacket communicating with said outlet.

16. A blower, comprising a casing having 110 a steam inlet chamber, an inlet chamber for a cooling agent and an outlet for said agent, a blower-tube extending into said casing and rotatably arranged therein, said tube communicating with said steam inlet chamber, a 115 rotary plug secured to the front end of the blower-tube, rotary operating means connected with said plug and extending outside of said casing, a cooling jacket surrounding the blower-tube and communicating with 120 said outlet, and a pipe arranged within the blower-tube and carried by said plug, said pipe communicating at its receiving end with said second-named inlet chamber and at its delivery end with said jacket.

17. A blower comprising a casing having a steam inlet chamber, an inlet chamber for a cooling agent and an outlet for said agent,

- a blower-tube extending into said casing and rotatably arranged therein, said tube communicating with said steam inlet chamber, a rotary plug secured to the front end of the 5 blower-tube, a rotary disk arranged in said second-named inlet chamber and spaced from said plug, pins connecting said disk with said plug, means for rotating said disk extending outside of said casing, a cooling jacket surrounding said blower-tube and communicating with said outlet, and a pipe arranged lengthwise within the blower-tube and connecting said second-named inlet chamber with said jacket.
- 10 18. A blower, comprising a casing having a steam inlet chamber, an inlet chamber for a cooling agent and an outlet for said agent, a blower tube communicating with said steam inlet chamber, a plug closing the front end of said tube, a cooling jacket surrounding the blower tube and communicating with said outlet, and a pipe arranged within the blower tube and removably secured in said plug, said pipe communicating at its receiving end with said second-named inlet chamber and at its opposite end with said jacket.
- 20 19. A blower, comprising a casing having a steam inlet chamber, an inlet chamber for a cooling agent and an outlet for said agent, a blower tube arranged in said casing and communicating with said steam inlet chamber, plugs closing the front and rear end of said tube, a cooling jacket surrounding the blower tube and communicating with said outlet, a water pipe disposed lengthwise in the blower-tube and removably supported in said plugs, said pipe communicating at its receiving end with said second-named inlet chamber and at its opposite end with said jacket, and a plug closing the rear portions of said jacket and said removable pipe.
- 25 20. A blower comprising a casing having separate inlets for steam and a cooling agent, a blower tube communicating with said steam inlet and having jet nozzles, a cooling jacket surrounding the blower tube, communicating with said cooling-agent inlet and having openings through which said jet nozzles pass, and means independent of said
- nozzles for connecting the jacket with the 50 blower tube.
21. A blower comprising a casing having separate inlets for steam and a cooling agent, a blower tube communicating with said steam inlet and having jet nozzles, means 55 for rotating the blower-tube, a cooling jacket surrounding the blower tube, communicating with said cooling-agent inlet and having openings through which said jet-nozzles pass, and means independent of said nozzles for transmitting the rotary movement of the blower-tube to said jacket.
22. A blower comprising a casing having separate inlets for steam and a cooling agent, a blower tube communicating with said 65 steam inlet and having jet nozzles, means for rotating the blower-tube, a cooling jacket surrounding the blower tube, communicating with said cooling-agent inlet and having openings through which said jet nozzles 70 pass, and connecting screws carried by the jacket and engaging the blower-tube.
23. A blower comprising a casing having separate inlets for steam and a cooling agent, a blower tube containing one or more expansion joints, said tube communicating with said steam inlet and having jet-nozzles, and a cooling jacket surrounding the blower tube, communicating with said cooling-agent inlet and having openings through 75 80 which said jet-nozzles pass.
24. A blower comprising a casing having separate inlets for steam and a cooling agent, a blower tube having telescopic sections forming one or more expansion joints, 85 said tube communicating with said steam inlet and having jet-nozzles, and a cooling jacket surrounding the blower tube, communicating with said cooling-agent inlet and having openings through which said jet-noz- 90 zles pass.

Witness my hand this 14th day of May,
1912.

JOHN MAGEE.
